(57) CLAIM

The ornamental design for a goblet-shaped wine decanter, as shown and described.

DESCRIPTION

FIG. 1 is a perspective view of a goblet-shaped wine decanter showing my new design:

FIG. 2 is a front view thereof;

FIG. 3 is a cross sectional view showing a section taken
along line 3-3 of FIG. 2;

FIG. 4 is a left side view thereof;

FIG. 5 is a cross sectional view showing a section taken
along line 5-5 of FIG. 4;

FIG. 6 is a top view thereof; and,

FIG. 7 is a bottom view thereof.

The broken lines in the drawings depict portions of the goblet-shaped wine decanter that form no part of the claimed design.
